(57) **CLAIM**

The ornamental design for a front cowl for motorcycles, as shown and described.

DESCRIPTION

FIG. 1 is a front elevational view of a front cowl for motorcycles showing our new design;

FIG. 2 is a top plan view thereof;

FIG. 3 is a bottom plan view thereof;

FIG. 4 is a right side elevational view thereof;

FIG. 5 is a left side elevational view thereof;

FIG. 6 is a right front perspective view thereof;

FIG. 7 is a left front perspective view thereof; and,

FIG. 8 is a reference view thereof, showing the front cowl in its state of use.

The broken lines illustrate environmental structure only and form no part of the claimed design.

1 Claim, 8 Drawing Sheets
